UNITED STATES PATENT OFFICE

CHARLES J. MULLETT, OF OTTAWA, OHIO

ANCHOR POST

Application filed February 20, 1929. Serial No. 341,438.

This invention relates to anchor posts, and is more particularly concerned with a tubular metal post formed to anchor its lower end in the ground without materially disturbing the solidity of the ground and its anchoring property and one which may be manufactured economically, installed with minimum labor and provide a securely anchored base.

Means is provided for guiding the post during its entry into anchored position in the ground and the anchoring means provide for and facilitate the sinking of the post base in the earth by rotatory motion providing a screw type of downward feed effective to sink the end of the post to a desired extent without materially weakening the entered earth as an anchoring base.

The invention consists in the structural features, arrangements and combinations hereinafter pointed out and claimed and is illustrated in the accompanying drawings forming a part hereof and in which:

Figure 1 is a perspective of a post formed according to my invention.

Figure 2 is a view in elevation of the post positioned for insertion in a guiding bore in the earth preliminary to its rotated earth penetrating movement to anchored position.

Figure 3 is a similar view of the post as rotated to anchored position, the helical path of the rotated cutting and anchoring wings being indicated.

Figure 4 is a horizontal sectional view through the tubing looking down on the cutting and anchoring wings.

My construction provides a post 1 of tubular metal formed at its base with lateral offset separated wings 2 and 3 at diametrically opposite sides of the post, these wings having sharply beveled forward cutting edges 4 and having their faces lying in the plane of a continuous helix containing said faces so that they present an earth entering portion 2 and a following portion 3 of flat helix traversing the same helical path.

This tubular post with its wings may be cast integrally but is preferably formed and as shown is of malleable iron having its lower end split longitudinally in its diameter and outturned and shaped, as by die pressing, to

provide the wings 2 and 3, the forward or earth entering edges 4 of these wings or at least of the earth entering wing 2, being sharply beveled to provide a cutting edge.

The tubular metal post thus formed is provided with a depending centering plug 5 or wood or other material having an external diameter approximating the internal diameter of the tubing and inserted in its lower end to extend downwardly in the longitudinal axial line of the post.

With a post thus arranged, a bore 6 approximating the diameter of the post tube is first made in the earth at the point of selected placement for the post. The centering plug 5 is inserted in this bore and the post 1 is engaged by a suitable tool such as a pipe wrench, and rotated. The sharp edge 3 of the lowermost helix wing 2 will penetrate the earth bordering the centering bore 6 and the helical form of the wing 2, as rotation of the post is continued, will draw the lower end of the post downwardly in the bore 6, the upper helix wing 3 following in the path previously cut by the entering wing 2 until the post has been rotated and "screwed down" by the helical wings to the desired depth.

Since both wings traverse a common helical path cut in the earth, the latter is not broken up and its anchoring solidity is not materially affected. The centering plug guides the wings and serves to maintain them in the direction of earth penetration of the guiding bore 6 which may have a depth selected to coincide with the extent of earth penetration of the tubular post, with the plug 5 extending and forced into the earth beyond the lower end of a bore 6 to afford further anchorage. While the post is intended primarily for anchorage in an earth base, it is, in principle, operable with respect to other supporting bases penetrable by its wings as for example, concrete or cement prior to setting.

With the plug 5 preceding the wings, a pre-formed bore will be presented whether or not the hole 6 is formed previous to the insertion of the plug or by its insertion. The area to be penetrated by the helix wings is therefore restricted to the area bordering this bore. With the plug 5 having a diameter substan-

tially coincident with the internal diameter of the cylinder 1, which itself is of uniform diameter, the outer walls of the latter on entering the preformed bore of slightly less diameter, will tend to force the walls of the bore outwardly as the wings and the lower end of the cylinder enter the bore, thus compacting the earth area bordering the bore and solidifying this area during the slicingly penetrative cutting action of the beveled edge 4 of the helix blade.

The form of the post as described and illustrated represents a preferred structural embodiment, but is intended as illustrative rather than restrictive of the invention and may be modified to suit different conditions of manufacture and use in consonance with the spirit of the invention and the scope of the appended claims.

20 What I claim, therefore, and desire to secure by Letters Patent is:

1. A cylindrical tubular metal post of uniform diameter having its lower end formed with opposed wings outstanding laterally from its periphery at its lower end in planes forming portions of a common helical path and having an axially aligned cylindrical extension depending from its lower end and substantially coincident in diameter with the 25 internal diameter of the post.

2. A cylindrical tubular metal post of uniform diameter having its lower end split in the line of its diameter and outturned and shaped to provide a pair of opposed transverse earth slicing and post anchoring wings outstanding laterally from its periphery at its lower end in planes forming portions of a common helical path centered on the axis of the tubular post, and a cylindrical centering 35 plug seating in and depending from the lower end of said post having a diameter substantially coincident with the internal diameter thereof.

3. A post having a cylindrical tubular 45 lower end of uniform diameter split in the line of its diameter and outturned and shaped to provide a pair of opposed earth cutting and post anchoring wings outstanding laterally from its periphery at its lower end in 50 planes forming portions of a common helical path centering on the axis of the tubular lower end of the post, and a cylindrical centering extension depending from the lower end of said lower tubular end having a diameter substantially coincident with the internal 55 diameter of said tubular end.

4. A post comprising a hollow metal cylinder of uniform diameter having opposed anchoring and earth slicing wings outstanding 60 laterally from its periphery at its lower end with their upper and lower faces in planes forming portions of a common helical path and with the lowermost of said wings provided with a beveled earth entering cutting 65 edge, and a cylindrical plug fitting in and de-

pending from the lower end of said cylinder having a diameter substantially coincident with the internal diameter of said cylinder and causing the larger external diameter of the earth entering lower end of said cylinder to force outwardly and compact the earth in the area entered by said wings.

Signed at Leipsic, in the county of Putnam and State of Ohio this sixth day of February, A. D. 1929.

CHARLES J. MULLETT.
